ANDREW H. CANDEE, OF PITTSBURGH, PENNSYLVANIA, ASSIGNOR TO WESTINGHOUSE ELECTRIC & MANUFACTURING COMPANY, A CORPORATION OF PENNSYLVANIA.

SYSTEM OF CONTROL.

1,367,118.

Specification of Letters Patent.

Patented Feb. 1, 1921.

Application filed June 15, 1917. Serial No. 174,933.

To all whom it may concern:

Be it known that I, ANDREW H. CANDEE, a citizen of the United States, and a resident of Pittsburgh, in the county of Allegheny and State of Pennsylvania, have invented a new and useful Improvement in Systems of Control, of which the following is a specification.

My invention relates to systems of control 10 and particularly to systems of control for electric railway vehicles.

One object of my invention is to provide a system of the above indicated character that shall open the circuit of a motor under 15 predetermined conditions and prevent the operation of the motor until the motor-governing controller is returned to the "off" position.

Another object of my invention is to provide 20 a system of control for an electric motor that shall be provided with a line switch for closing the motor circuit and means for preventing the operation of the line switch under predetermined conditions.

Another object of my invention is to provide 25 a control system of the above indicated character that shall be provided with a switch for closing the motor circuit, a controller for governing the operation of the motor, an overload-trip switch and a plurality of interlock switches for releasing the line switch under predetermined conditions, and means for preventing the operation of the line switch until the controller is 30 turned to the "off" position, in case the line switch is released when the controller is in an operative position.

In electric-railway-vehicle-control systems now in service are severally embodied means 40 for energizing a line switch for completing a circuit through a motor when the motor-governing controller is moved to its first operative position and means, as, for example, door-interlock switches or a slip segment 45 of well known type, for releasing the line switch under predetermined conditions when the controller is in an operative position. However, in each of the systems of the type above indicated, the line switch is 50 operated to complete the motor circuit momentarily when the controller is returned through the first operative position and thus gives the car an unnecessary jolt.

In a system embodying my invention, a

line switch is operated to complete the motor 55 circuit when the controller is in the first operative position but means is provided, in case the line switch is released when the controller is in an operative position, for preventing the operation of the line switch 60 again until the controller is returned to the "off" position and thus preventing the unnecessary jolt to the vehicle that is encountered in systems now in service, when the controller is returned to the first operative 65 position.

The single figure of the accompanying drawing is a diagrammatic view of a control system embodying my invention.

In the accompanying drawing, a motor 1, 70 embodying an armature 2 and a field winding 3, is adapted to be connected across a supply circuit comprising a trolley conductor 4 and a ground-return conductor 5 by means of a line switch 6 and a controller 7.

The controller 7 embodies a contact segment 8 for engaging contact fingers 9 and 10, in the various operative positions of the controller, to connect the various auxiliary 80 control circuits to the trolley conductor 4, contact segment 11, which is adapted to engage the contact fingers 12, 13, 14, 15 and 16 for excluding resistors R1, R2 and R3 from the circuit of the motor 1, and a slip-contact segment 17, which is adapted to engage the contact fingers 18 and 19, when the controller is moved in a forward direction, for a purpose to be described later. The slip-contact segment 17 is mounted 90 upon a slip ring 20 that is frictionally attached to the controller 7 and is provided with two projections 21 and 22 which are respectively adapted to engage a stationary pin 23 when the controller is moved in a 95 forward and in a reverse direction. Thus, when the controller is moved in a forward direction, the projection 21 engages the pin 23, and the contact segment 17 is maintained in engagement with the contact 100 fingers 18 and 19, and, when the controller is moved in a reverse direction a predetermined distance, the projection 22 engages the pin 23, and the contact segment 17 is disengaged from contact with the fingers 105 18 and 19.

The line switch 6 is provided with an operating coil 24 and two interlock switches

25 and 26, for a purpose to be described later. An auxiliary switch 27, which is adapted to bridge contact terminals 28 when in an operative position and to bridge contact terminals 29 when released, is provided for permitting the energization of the line switch 6 in the first position of the controller 7 and for preventing the operation of the line switch until the controller is returned to 10 the "off" position in case the line switch is released when the controller is in an operative position.

Two door interlock switches 30 and 31 and an overload-trip switch 32 are provided 15 for deenergizing the coil 24 of the line switch in case a door of the vehicle is opened, or in case an excessive current passes through the motor. The coil 24 of the line switch 6 is adapted to be connected 20 across a portion of a resistor 33, which is connected between the supply-circuit conductors, and the coil of the auxiliary switch 27 is adapted to be connected across the supply circuit through a resistor 34.

25 Assuming the various control apparatus to be in the position illustrated in the drawing, the motor 1 may be connected across the supply circuit when the master controller 7 is moved to position *a*. In position 30 *a* of the controller 7, a circuit is completed from the trolley conductor 4 through the contact fingers 9 and 10—which are bridged by the contact segment 8—a portion of resistor 33, overload-trip switch 32, coil 24 of 35 the line switch, contact terminals 29—which are bridged by the movable member of switch 27—contact fingers 18 and 19—which are bridged by the slip segment 17—and interlock switches 30 and 31 to the ground-return conductor 5. Thus, the line switch 6 is operated to complete a circuit from the trolley conductor 4 through the line switch 6, contact fingers 12 and 13—which are bridged by the contact segment 11—resistors 45 R1, R2 and R3, coil of the overload-trip switch 32 and motor 1 to the ground-return conductor 5.

When the line switch 6 is operated, a circuit is completed through the coil of the auxiliary switch 27 from the trolley conductor 4 through contact fingers 9 and 10—which are bridged by the contact segment 8—resistor 34, interlock switch 26 and the coil of the auxiliary switch 27 to the ground-return conductor 5. Thus, the auxiliary switch 27 is operated to break the circuit previously traced through the coil 24 of the line switch 6 and to complete a holding circuit for itself through the contact terminals 55 28. A holding circuit for the line switch 6 is completed through the interlock switch 25 previous to the opening of the energizing circuit therefor, by the operating of the auxiliary switch 27.

60 In positions *b*, *c* and *d* of the controller 7,

the resistors R1, R2 and R3 are successively excluded from the circuit of the motor 1.

In case the circuit for the coil 24 of the line switch 6 is broken by means of the slip segment 17 or the overload-trip switch 32, or the door interlock switches 30 and 31, the line switch is released and the circuit of the motor 1 is broken. The holding circuit for the coil of the auxiliary switch 27 from the trolley conductor 4 through the contact fingers 9 and 10—which are bridged by the contact segment 8—resistor 34, contact terminals 28—which are bridged by the relay 27—and the coil of the relay 27 to the ground-return conductor 5 is maintained 70 closed until the controller 7 is returned to the "off" position to disconnect the contact segment 8 from the contact fingers 9 and 10. Inasmuch as the line switch 6 cannot be operated while the auxiliary switch 27 is in 75 an operative position, it is apparent that, if the line switch is released when the controller is in an operative position, it is impossible to operate the line switch and complete the motor circuit until the controller 80 is returned to the "off" position.

Modifications in the system and arrangement and location of parts may be made within the spirit and scope of my invention and such modifications are intended to be 85 covered by the appended claims.

I claim as my invention:

1. In a system of control, the combination with a motor and a controller for governing the operation of the motor, of means for 100 breaking the circuit of the motor under predetermined conditions when the controller is in an operative position, and a switch energized in all operative positions of said controller for preventing the reclosure of 105 the motor circuit until the controller is returned to the off position.

2. In a system of control for an electric vehicle, the combination with a motor, and a controller for governing the operation of 110 the motor, of means for opening the motor circuit in case a door of the vehicle is opened or the controller is moved in a reverse direction a slight amount from an operative position, and means for preventing the reclosing of the motor circuit until the controller is moved to the off position.

3. In a system of control for an electric vehicle, the combination with a motor, a line switch for completing the motor circuit, and 115 a controller for governing the operation of the motor, of an auxiliary switch for effecting the operation of the line switch to complete the motor circuit when the controller is in the first operative position and for 120 preventing, when energized, the operation of the line switch when the same has been released until the controller is returned to the off position.

4. In a system of control, the combina- 125

tion with a motor, a line switch for completing the circuit of the motor, and a controller for governing the operation of the motor, of means for releasing the line switch, under predetermined conditions, to open the motor circuit when the controller is in an operative position, and an auxiliary switch energized in all operative positions of the controller for preventing the operation of the line switch until the controller is moved to the off position.

5. In a system of control, the combination with a motor, an electrically-operated line switch for completing the circuit of the motor, and a controller for governing the operation of the motor, of means comprising interlock switches for deenergizing the coil of the line switch, under predetermined conditions, when the controller is in an operative position, and an auxiliary switch initially closed by the line switch and adapted to prevent, when energized, the operation of the line switch until the controller is moved through the off position.

25. 6. In a system of control, the combination with a motor, an electrically-operated line switch for completing the circuit of the motor, and a controller for governing the operation of the motor, of an overload-trip switch inserted in the circuit of the operating coil for said line switch and having an energizing coil in the motor circuit, and means for preventing, when energized, the operation of the line switch until the controller is returned to the off position in case the line switch is released by the overload-trip switch when the controller is in an operative position.

40. 7. In a system of control, the combination with a dynamo-electric machine and a controller for governing the operation thereof, of means for closing the circuit thereof, and initially inoperative means to permit the action of the first means in the first operative position of the controller and thereafter operative to prevent repetition of such action after the opening of the first

means until the machine circuits resume their original condition.

8. In a system of control, the combination with a dynamo-electric machine and a controller therefor, of means for closing the machine circuit, and an initially inoperative switching device to permit the action of said means in the first operative position of the controller and thereafter operative to prevent repetition of such action after the opening of said means whenever the controller occupies an operative position.

9. In a system of control, the combination with a dynamo-electric machine and a controller therefor, of a switch for closing the machine circuit, and a relay device having contact members in the switch-controlling circuit and having an actuating coil energized by the closure of said switch, and an additional energizing circuit for said device.

10. In a system of control, the combination with a dynamo-electric machine and a controller therefor, of a switch for closing the machine circuit, and a relay device having contact members in the switch-controlling circuit and having an actuating coil energized by the closure of said switch, and a holding circuit for said device energized only upon the closure thereof under operating conditions.

11. In a system of control, the combination with a dynamo-electric machine and a controller therefor, of a switch for closing the machine circuit, means dependent upon the current traversing the machine for releasing said switch, and an initially inoperative relay device to permit the closure of said switch in the first operative position of the controller and thereafter operative to prevent re-closure after the operation of said means until the controller occupies a predetermined position.

In testimony whereof, I have hereunto subscribed my name this 28th day of May, 1917.

ANDREW H. CANDEE.
